UNITED STATES PATENT OFFICE.

HARRY SUTTON PELL, OF TORONTO, CANADA.

PULLEY.

SPECIFICATION forming part of Letters Patent No. 605,557, dated June 14, 1898.

Application filed June 12, 1897. Serial No. 640,421. (No model.)

To all whom it may concern:

Be it known that I, HARRY SUTTON PELL, of the city of Toronto, in the county of York, in the Province of Ontario, Canada, have invented certain new and useful Improvements in Pulleys, of which the following is a specification.

My invention relates to improvements in pulleys; and the object of the invention is to produce a light, cheap, and strong pulley and in which the peripheral face may be always rendered perfectly circularly true; and it consists, essentially, in forming the peripheral face of the pulley preferably of wood bent into shape and provided with an inner sheathing of sheet metal having inturned edges or beads formed on it to bind the wood in place, the spokes being also provided with cross-heads, which extend through grooves in the inner peripheral face of the wooden periphery, the hub being preferably divided centrally on a line with the spokes and the parts being otherwise constructed and arranged as hereinafter more particularly explained.

Figure 1 is a sectional perspective view of a pulley constructed in accordance with my invention. Fig. 2 is a center section parallel to the face of the pulley. Fig. 3 is a longitudinal section through one of the strips of wood forming one-half of the peripheral face of a split pulley. Fig. 4 is an enlarged cross-sectional detail through the periphery. Fig. 5 is a cross-sectional detail of an alternative form of the rim.

In the drawings like letters of reference indicate corresponding parts in each figure.

A represents the peripheral face of the pulley, which is preferably formed of wood and made, when formed as a split pulley, preferably in two halves with notches a to permit of the bending of the strip of wood from the straight piece, as shown in Fig. 3, into the arc desired. Supplemental notches a' are also provided. The edges of the strips have the inner projecting flanges or beads a^2 and the outer face-grooves a^3 outside of the flanges a^2 .

B are the spoke cross-heads, made of malleable, cast, or other suitable material, which have preferably inwardly-turned peripheral lips b , bent in the form shown, so as to securely bind the spoke cross-heads to the

flanges a^2 of the peripheral face A, and thus provide for the necessary grip in driving the peripheral face. The spoke cross-heads B fit within the notches a' , thus serving to further and more securely form a driving connection between the spoke cross-heads and the face of the pulley.

C is a metal sheathing, preferably made of sheet iron or steel and placed circumferentially within the face A. The edges of the sheathing are preferably turned inwardly into the grooves a^3 , thus serving to form retaining-flanges b' to prevent the displacement of the face A. The inturned beads b^2 of the flanges b' fit into the edge grooves a^3 of the face A. The interior sheathing and face serve to form the rim, and such interior sheathing gives a solid foundation or rigidity to the wood face, without which it would be too weak to allow of the pulley being made light, as if the rim were entirely formed of wood. The metal sheathing also serves to hold the spoke cross-heads in place and to prevent any warping, twisting, or splitting of the wood and at the same time give a neat and workman-like finish to the edges of the under face and insure safety from accidents or bursting at high speed. I am also enabled to turn the wood face perfectly true. The spoke cross-heads and flanges may be secured to the face by screws b^3 and b^4 .

The spoke cross-heads have formed centrally on their inner side the threaded bosses B', upon which are screwed the hollow spokes D. The hub is preferably cast in two parts E and E', which are provided with flanges e and bolts e' to connect them together. The dividing-point of the hub is on a plane through the axes of the spokes. Each part E of the hub is provided with radial bosses having recesses e^3 , into which are fitted the ends of the spokes D. This form is suitable for either a split or solid pulley. In a split pulley the sheathing C would of course be divided slightly to one side of the abutting ends of the face.

It will be noticed from the construction shown that the pulley is practically metallic, combining, however, all the advantages of a wood face with metal foundation.

In the construction of my pulley it is not necessary to use glue or nails, and the spokes

cannot loosen by the shrinking or drying out of the wood, nor does damp affect the article in any way.

Although I describe one form of edge in order to confine and hold the face of the pulley in place, it will be understood that I do not wish to confine myself to any such form, as various other forms may be used and yet accomplish the object which I have in view—viz., to form a binding driving connection between the spokes and the rim and to furnish an annular chamber for the reception of the material forming the belt-face.

In Fig. 5 I show a cross-section of the rim in which annular corrugations are formed in the sheathing. This form may be used where a particularly strong pulley is desired.

Although I describe the face as formed of wood, it will be understood that it might be formed of any suitable plastic light material, such as wood-pulp or light composition, which could be readily placed within the annular chamber formed by the sheathing and then trued up after being dried.

25 In the form of divided hub shown it will be seen that the divided hub may be readily separated and a new hub of larger or smaller diameter of bore substituted for any required size of shaft.

30 In the form shown in Fig. 5 it will also be noticed that the turned-out flange is reinforced by being doubled back on itself.

What I claim as my invention is—

1. In combination in a pulley, the belt-face of light material, and a metal sheathing having side flanges, and beaded edges fitting the edges of said light material, substantially as described.

2. In a pulley, in combination the face provided with edge flanges, and the broad cross-notches made across the interior wall of the face, the spoke cross-heads fitting into such notches, the interior sheathing having retaining edges to hold the face in place the spokes and means for connecting the spokes to the cross-heads as and for the purpose specified.

3. In a pulley, in combination the face provided with edge flanges, and the broad cross-notches made across the interior wall of the

face, the spoke cross-heads having threaded 50 central bosses, the interior sheathing through which the bosses extend and the tubular spokes into which the threaded bosses extend and a suitable hub to receive the inner ends of the spokes as and for the purpose specified. 55

4. In a pulley, in combination the face provided with edge flanges, and the broad cross-notches made across the interior wall of the face, the spoke cross-heads fitting into such notches, the interior sheathing having retaining edges to hold the faces in place the spokes and means for connecting the spokes to the cross-heads and the hub divided on the plane of the axes of the spokes and having flanges and bolts for securing the two parts of such 65 hub together as and for the purpose specified.

5. In a pulley in combination, the face provided with edge flanges, the broad cross-notches made across the interior wall of the face, the spoke cross-heads fitting into such 70 notches and provided with inwardly-turned lips designed to embrace the flanges, the spokes suitably secured to the same and the interior sheathing through which the spokes extend as and for the purpose specified.

6. In a pulley, in combination, the face provided with the inner circumferential edge flanges and the outer circumferential edge grooves located within the flanges and the interior sheathing provided with the edge 80 flanges and beads at their inner ends fitting within the grooves of the edges of the face, the spokes, and hub, and means for connecting the spokes to the interior sheathing as and for the purpose specified. 85

7. A rim for a pulley comprising a metal interior sheathing having inwardly - turned flanges reinforced by being turned back upon themselves and a filling of suitable material for such chamber forming the belt-face, said 90 reinforced edges extending up flush with the face of said filling and over the edge thereof, substantially as described as and for the purpose specified.
